UNITED STATES PATENT OFFICE.

JOHN D. THOMPSON, OF BRINKLEY, ARKANSAS.

BRAKE-RIGGING SAFETY APPLIANCE.

1,163,046.

Specification of Letters Patent. Patented Dec. 7, 1915.

Application filed May 18, 1915. Serial No. 28,864.

To all whom it may concern:

Be it known that I, JOHN D. THOMPSON, a citizen of the United States, residing at Brinkley, in the county of Monroe and State 5 of Arkansas, have invented certain new and useful Improvements in Brake-Rigging Safety Appliances, of which the following is a specification.

My invention relates to a safety appliance 10 or supporting means for use in connection with trucks of railway cars or the like, for holding up the different parts of the brake rigging, in case they should drop, due to breakage or other accidents.

15 An important object of the invention is to provide means of the above mentioned character, having no parts to work loose, separate or become deranged, whereby the appliance is always retained in an operative 20 condition.

A further object of the invention is to provide means of the above mentioned character, which are simple in construction, inexpensive to manufacture, strong and durable.

25 Other objects and advantages of the invention will be apparent during the course of the following description.

In the accompanying drawings forming a 30 part of this specification and in which like numerals are employed to designate like parts throughout the same, Figure 1 is a plan view of a truck equipped with my safety appliance, Fig. 2 is a longitudinal sectional view taken on line 2—2 of Fig. 1, 35 Fig. 3 is a perspective view of the safety appliance removed, and, Fig. 4 is a detail side elevation of a brake rod supporting element.

In the drawings, wherein for the purpose 40 of illustration is shown a preferred embodiment of my invention, the numeral 5 designates a railway car truck, as a whole, comprising end frames 6, carrying journal boxes 7, receiving the ends of axles 8, which carry 45 wheels 9, as shown. The end frames 6 are rigidly connected by a transverse beam or member 10, having springs 11 arranged thereon, to be engaged by an upper transverse beam or member 12. While this is the 50 preferred construction of the truck, in connection with which my safety appliance is used, it is to be understood that the invention is in no sense restricted to the use of this particular type of truck.

55 In the claims, the beam or beams 10 and 12 will be referred to as the transverse body

portion of the truck. Arranged upon opposite sides of the transverse body portion or beams 10 and 12 are brake beams 13, suspended by links or hangers 14, secured to transverse bars 15, mounted upon the transverse beam 12. At their ends, the brake beams 13, carry brake shoes 16, to contact with the wheels 9. Pivots connected with one brake beam 13, as shown at 17, is a lever 18, the lower end of which has pivotal connection with a link or rod 19, pivotally connected with a lever 20. This lever is pivotally connected between its ends, as shown at 21, with the other brake beam 13, and its upper end is pivotally connected with a bracket 22, which is rigidly connected with the beam 12. It is thus apparent that when the upper end of the brake lever 18 is swung forwardly, the brake beams 13 will be swung 75 away from each other for applying the brakes, as is customary.

My safety appliance comprises inverted preferably approximately U-shaped hangers, or supporting members 23, adapted to 80 straddle the transverse body portion or beams 10 and 12, to be supported thereby. Near its lower end, these hangers carry lateral extensions 24, having apertures 25, for receiving the ends of the brake beams 13. 85 These hangers do not in any way interfere with the operation of the brake beams, nor their normal suspension by the links 14 or the like. The hangers 23 are arranged inwardly of and near the wheels 9, and are 90 provided beneath the extensions 24 with apertured knuckles 25', receiving rods 26. These rods are connected by links 27, arranged outwardly of the hangers 23 and provided with eyes 28, surrounding the ends of 95 the rods 26. The outer ends of the rods 26 are apertured for receiving cotter pins 29 or the like. The rods 26 are also apertured inwardly of and near the knuckles 25' to receive cotter pins 30 or the like, the two sets 100 of cotter pins serving to prevent longitudinal displacement of the hangers with relation to the rods. The rods 26 carry depending supporting members 31, apertured at 32 for receiving the link or rod 19, to support 105 it in the event that it should become disconnected from either of the levers 18 or 20.

From the foregoing description it is obvious that upon the links 14 breaking, the 110 brake beams 13 will be held within the apertured extensions 24 and supported thereby. It is also apparent that the link or rod 19

2
will be supported in case the same should break or become disconnected from one of its levers.

It is to be understood that the form of my invention herewith shown and described is to be taken as a preferred example of the same, and that various changes in the shape, size, and arrangement of parts may be resorted to without departing from the spirit 10 of the invention or the scope of the subjoined claims.

Having thus described the invention, I claim:—

1. A safety appliance for brake rigging, comprising inverted approximately U-shaped hangers adapted to be arranged upon and straddle the transverse body portion of a truck and provided near their lower ends with lateral extensions which are apertured 20 for receiving the brake beams, substantially as described.

2. A safety appliance for brake rigging, comprising inverted approximately U-shaped hangers adapted to be arranged upon

and straddle the transverse body portion of a truck and provided near their lower ends with laterally extending apertured extensions for receiving the brake beams, and rods connecting the lower ends of one hanger with the lower ends of the other hanger. 30

3. A safety appliance for brake rigging, comprising inverted approximately U-shaped hangers adapted to be arranged upon and straddle the transverse body portion of a truck and provided near their lower 35 ends with apertured lateral extensions for receiving the brake beams, laterally spaced rods connecting the lower ends of one hanger with the lower ends of the other hangers, and apertured supporting members 40 carried by the rods to receive a brake link therethrough.

In testimony whereof I affix my signature in presence of two witnesses.

JOHN D. THOMPSON.
